UNITED STATES PATENT OFFICE.

WILLIAM H. EMOND, OF BOSTON, MASSACHUSETTS.

TURN-PLATE FOR VEHICLES.

SPECIFICATION forming part of Letters Patent No. 601,559, dated March 29, 1898.

Application filed October 5, 1897. Serial No. 654,166. (No model.)

To all whom it may concern:

Be it known that I, WILLIAM H. EMOND, a resident of Boston, in the county of Suffolk and State of Massachusetts, have invented 5 a new and useful Improvement in Carriage Safety-Plates, of which the following, taken in connection with the accompanying drawings, is a specification.

My invention is an improvement on the device patented to me December 29, 1896, No. 574,313, and relates to improvements in safety-plates and turn-plates for vehicles, being especially adapted to vehicles of large size.

The objects of my invention are to render 10 the safety-plate strong and compact, so that it will protect all the parts required, and also to facilitate the turning of vehicles of large size and to provide a beveled turn-plate whereby a strong bearing may be obtained at the greatest point of strain. I attain these objects by 15 means of the mechanism illustrated in the accompanying drawings, in which—

Figure 1 is a side elevation, in part section, of the gearing with safety-plate. Fig. 2 is a 25 perspective view of the safety-plate. Fig. 3 is a top view of the turn-plate and axle made integrally or all in one piece. Fig. 4 is a sectional view of the turn-plate centrally through the stud 6 and ridge-piece 8, showing the form 30 employed when the axle is detached.

Similar numerals denote similar parts throughout the several parts.

1 is the upper plate, of metal, provided with reach-plates 2, and on the front the head-block 35 3, bolted thereto.

4 is the turn-plate, secured to the forward axle by means of the clamps 5 and beveled on the under side and having greater thickness at the axle, where the greater strain comes, 40 and making thereby a stronger bearing.

6 is a stud which forms the point of oscillation and is arranged in a suitable circular recess 7 in the upper plate 1. I may make this turn-plate integral with the axle, as shown in 45 Fig. 3, or I may make it detachably applied to the axle, as shown in Fig. 4.

8 is a ridge on the turn-plate 4, which serves to strengthen it. 9 is the safety-plate, which is bolted to the upper plate 1 under the turn- 50 plate 4 by the bolts 10.

11 is a rubber cushion upon the inner surface of the safety-plate 9, the same being covered by a thin plate of steel 12.

The safety-plate is triangular in form, with

curved base, and has flanges 13 13 on either 55 side which run from the apex 14 to a point above the inner surface of sufficient height to allow the flanges to completely cover the rubber cushion 11 and steel plate 12.

The upper plate 1 is provided with a recess 60 15 to allow the ridge 8 on the turn-plate 4 to operate therein.

16 are bosses forming part of plate 1 on either side and beveled to allow of even bearing with the safety-plate 9 and through which 65 pass bolts 10 10.

17 are bosses on outer surface of safety-plate 9, which are made level to receive the nuts on bolts 10.

The sloping sides of the safety-plates allow 70 the turn-plate to be made thicker near the axle, where the greatest strain comes.

It will thus be seen that the safety-plate with its flanges protects all the parts and allows a turn-plate to be used which can endure 75 the strain of heavy vehicles.

Having described my invention, what I desire to secure by Letters Patent and claim is—

1. The turn-plate, joined to the axle, having stud 6 and ridge 8, in combination with 80 recessed upper plate 1, and the safety-plate 9, provided with flanges 13, bolted to said upper plate beneath said turn-plate, substantially as specified.

2. The combination of the turn-plate with 85 means for attachment to the axle, having stud 6 and ridge 8, with recessed upper plate having reaches 2, and stud-socket 7, the flanged safety-plate, bolts for securing the same, steel cover-plate 12, and elastic cushion 11, substantially as specified.

3. A turn-plate joined to the axle, having stud 6 and ridge 8, beveled underneath to afford greatest strength at the point nearest the axle, in combination with the triangular 95 safety-plate provided with flanges sloping to the apex, and a recessed upper plate to which said safety-plate is attached by bolts, substantially as specified.

In testimony whereof I have signed my 100 name to this specification, in the presence of two subscribing witnesses, on this 23d day of September, A. D. 1897.

WILLIAM H. EMOND.
